(57) **CLAIM**

The ornamental design for a workbench, as shown and
described.

DESCRIPTION

FIG. 1 is a front perspective view of a workbench in
accordance with the invention;

FIG. 2 is a front view thereof;

FIG. 3 is a right side view thereof that is identical/sym-
metrical to the left side view thereof;

FIG. 4 is a rear view thereof;

FIG. 5 is a top view thereof;

FIG. 6 is a bottom view thereof;

FIG. 7 is a top view thereof as in FIG. 5 but with the
benchtop removed for convenience of illustration; and,
FIG. 8 is a bottom view thereof as in FIG. 6 but with the
shelf removed for convenience of illustration.

That which is depicted in solid lines in the drawing repre-
sents the claimed invention and that which is depicted in
broken lines in the drawing forms no part of the claimed
invention.

Portions of bottom views that are not shown in the drawing
are plain and unornamented.
